CLAIM

The ornamental design for a golf ball marker, as shown, and described.

DESCRIPTION

FIG. 1 is a rear perspective view of the golf ball marker;
FIG. 2 is a top view of the golf ball marker;
FIG. 3 is a bottom view of the golf ball marker;
FIG. 4 is a rear view of the golf ball marker;
FIG. 5 is a side view of the golf ball marker wherein the
opposite side view is identical; and,
FIG. 6 is a front view of the golf ball marker.
